UNITED STATES PATENT OFFICE.

JOHN K. McLAUGHLIN, OF PHILADELPHIA, PENNSYLVANIA, ASSIGNOR OF
ONE-HALF TO LEWIS H. TAYLOR, JR., OF SAME PLACE.

CONDUIT FOR ELECTRICAL CONDUCTORS.

SPECIFICATION forming part of Letters Patent No. 269,086, dated December 12, 1882.

Application filed January 27, 1882. (No model.)

To all whom it may concern:

Be it known that I, JOHN K. McLAUGHLIN, a citizen of the United States, residing at Philadelphia, in the county of Philadelphia and State of Pennsylvania, have invented certain new and useful Improvements in Conduits for Electrical Conductors; and I do hereby declare the following to be a full, clear, and exact description of the invention, reference being had to the accompanying drawings, which form part of this specification, in which—

Figure 1 is a perspective of my invention. Fig. 2 is a detailed perspective. Fig. 3 is a transverse vertical section. Fig. 4 is a broken elevation of two conduit-sections and joint-coupling therefor, the latter being partly sectional; and Fig. 5 is a transverse vertical section of one of the conduit-sections.

My improvements relate to a construction of electrical-conductor conduits, whereby the same may be cast without coring, and after being laid readily separated longitudinally for the purpose of securing access to their contents.

In an application of even date herewith for Letters Patent I have shown an electrical-conductor conduit composed of pipes or tubes rectangular in cross-section and not divided longitudinally. In this present application my improvements consist in making such conduit-sections longitudinally divided or separated at two of their corners, each half-section thus being composed of a side and a top or bottom, the two halves being held together by joint-couplers at their ends and by bolts and lugs located midway of the sections or at two or more points between such ends.

Referring to the accompanying drawings, A indicates a conduit composed of sections B, which are formed with external ribs, b, and fastened together by joint-couplers C, the latter formed in two halves, c c, said collars having a rib, c', and grooves c² c² for the reception of the ribs b b, their parts being secured together by bolts c³ c³, passed through openings in their bent ends c⁴.

The sections B are made longitudinally divided at two of their corners—*i. e.*, at one upper corner and the diagonally-opposite lower corner. Each division thus consists of one vertical side, b', and the horizontal top or bottom piece, b² or b³. The edges of the divisions

are rabbeted, as shown, so as to fit snugly to form a tight joint at such meeting edges. The parts are provided midway or at two or more points between their ends with lugs d d, having openings for the passage of bolts D, whereby they are drawn powerfully together.

The joint-couplers C C, which are of the same construction as those described and claimed in my other application, in the present case not only form end couplings for the sections, but also serve to clamp the divisions of said sections together, and thus make tight joints on the longitudinal dividing-lines of such sections.

E represent vertical partitions, with shelves e for the support of conductors contained in the conduit, and F are gates in the sides of said conduits for affording access to the contents of the latter. These partitions and the shelves and gates, being described and claimed in my aforementioned other application, are not herein claimed by me.

Under some circumstances, where the gates would not afford ample enough access to the conductors, the conduit-sections may be longitudinally separated, the top and one side or the bottom and its attached side being taken away.

Under some circumstances it may be desired to remove an entire section of the conduit without disturbing the continuity of the conductors laid therein. The construction herein described will permit such removals, which would not be practicable if the conduit-sections were each in one whole piece. Another advantage of this divisional form of conduits is that the casting of same can be effected without coring, which is necessary if each section be formed of but a single piece.

The conduit thus constructed, being rectangular in cross-section, is susceptible of division into compartments of equal size, which a circular conduit does not readily permit. The sides being straight, gates for entrance may be more readily formed and be more easily fitted and moved than if made on curved sides. The two divisions which compose each section being exactly alike, one pattern will answer for both and either division will serve for the top or bottom of the conduit, which will be found very convenient in laying and repairing the same.

I am aware that conduits for various purposes have heretofore been made of sections of

half-round pipe, such sections being coupled together; hence I do not claim the same, my invention being confined to angular sections, which when jointed together, form rectangular conduits which are susceptible of division into compartments of equal area, readily accessible through lateral openings.

What I claim as my invention is as follows:

In a conduit for electrical conductors, the combination of sections, each of which is made of two parts or divisions, both the divisions which constitute a section being exactly alike, having two straight sides at right angles to each

other, provided with external end ribs, with internally ribbed and grooved clamp-collars, 15 which embrace the ends of said sections and receive the external ribs on the divisions, substantially as shown and described.

In testimony that I claim the foregoing I have hereunto set my hand this 24th day of January, 1882.

JOHN K. McLAUGHLIN.
